CLAIM

The ornamental design for a massage head for a fascia gun, as shown and described.

DESCRIPTION

Figure 1.1 is a front view of a massage head for a fascia gun, showing my new design;

Figure 1.2 is a back view thereof;

Figure 1.3 is a left view thereof;

Figure 1.4 is a right view thereof;

Figure 1.5 is a top view thereof;

Figure 1.6 is a bottom view thereof; and

Figure 1.7 is a perspective view thereof.

The area colored in black in reproduction 1.6 depicts a portion of the massage head for a fascia gun that forms no part of the claimed design.

The broken lines in the drawings depict portions of the massage head for a fascia gun that form no part of the

(Continued)

claimed design. The deemphasized and half-tone portions within the broken line area forms no part of the claimed design.
